UNITED STATES PATENT OFFICE.

HERMANN C. G. REMANÉ, OF BERLIN, GERMANY, ASSIGNOR TO GENERAL ELECTRIC COMPANY, A CORPORATION OF NEW YORK.

FILAMENT-MOUNTING.

1,106,971.

Specification of Letters Patent. Patented Aug. 11, 1914.

Application filed September 13, 1910. Serial No. 581,828.

To all whom it may concern:

Be it known that I, HERMANN C. G. REMANÉ, a subject of the Emperor of Germany, residing at Berlin, Germany, have invented certain new and useful Improvements in Filament-Mountings, of which the following is a specification.

My invention relates to filament mounting and will be found advantageous in the 10 mounting of filaments for incandescent lamps, particularly fine, fragile filaments.

For a complete understanding of my invention, reference is to be had to the following specification and the accompanying 15 drawing in which is disclosed an embodiment of my invention as applied to an incandescent lamp; but I desire it to be understood that this embodiment is illustrative merely and that the invention can be carried 20 out and applied in other ways within the scope of the appended claims.

Figure 1 of the drawing is a perspective view of a lamp with filaments in the mounting of which holding devices embodying my 25 invention are employed; and Fig. 2 is a fragmentary view of one of such holding devices on an enlarged scale.

The invention is shown as embodied in an apparatus having two "looped" filaments 30 each comprising two curved lengths or sections; but it may, of course, be employed in apparatus having any number of filaments, whether in single lengths or sections, in loop form, or in the form of a continuous zig-zag 35 comprising any desired number of lengths or sections, or in other forms. In any of these cases, the filament sections may be straight, curved, or bent, etc.

The mount of the lamp shown in Fig. 1 40 comprises an ordinary glass stem or carrier D serving for the introduction of the leading-in wires l, l. To this stem is attached a member or standard e of glass or other suitable material on which are the various holding devices or arms comprised in the filament-supporting system. The individual loop shaped filaments a shown in Fig. 1 are supported at the ends of their legs by the conductive elements or supporting arms b 45 and at the point of curvature or bight of the loop by the open engaging portions or hooks of the holder arms c. The filament legs receive intermediate support from means sub-

stantially embracing them at about their middle, but open in one direction—which 55 may to advantage be toward the globe of the lamp. An anchor arm or shank with a forked end for engaging the filament is a simple holding-device embodying this idea. As shown, the middle holding-device d has 60 the form of a prolonged S, which is an easily and cheaply constructed form of fork. The holding devices d are attached to the standard e in approximately radial position so that they extend approximately perpendicular to the legs of the filaments. It is 65 desirable to make these middle holding devices of flexible or elastic material.

The simplification in construction resulting from the employment of such holding 70 means is self-evident. The filaments have only to be laid on an open holder, so that the tedious and consequently expensive operation of threading the filament through the holding device—necessary with ring-shaped or 75 other holding devices closed on all sides—is avoided. If the forked middle holding devices project farther from the axis of the supporting system than the points of attachment of the ends of the filaments and the engaging portion of the holders c, a tension on 80 the filaments when cold in an outward direction from the axis of the lamp may be caused. Such tension is found especially advantageous in making the connections between the filaments and the conductive elements b regardless of whether this be done 85 by fusing, soldering, or otherwise.

What I claim as new and desire to secure by Letters Patent of the United States, is,— 90

1. An anchor for filaments having a fork-shaped engaging portion, the opening of the fork being in the longitudinal direction of the anchor.

2. An anchor member for filaments having a fork-like engaging portion resembling in shape the letter S and consisting of a portion of said member twice bent back upon itself so as to bring the opening of the fork 95 in the longitudinal direction of the anchor. 100

In witness whereof, I have hereunto set my hand this 30th day of August, 1910.

HERMANN C. G. REMANÉ.
